UNITED STATES PATENT OFFICE

THOMAS S. S. WAGNER, OF GARDENA, CALIFORNIA

MACHINE FOR DISPLAYING ADVERTISING

Application filed August 6, 1930. Serial No. 473,470.

My invention relates to a machine for displaying advertising of the general type of my Patent 1,747,746, February 18, 1930. In this present invention I have a plurality of arms mounted on the same vertical pintle, which arms are stacked together in the form of a pack when in the extreme positions of movement, and each arm supports an advertising card so that the machine is designed to swing the arms in the arc of a circle from the initial to a terminal position and thus expose both sides of the cards. After the complete pack or stack of arms with the depending cards have been shifted to the terminal position the arms as a stack or group are returned to the initial position in the single operation.

In a machine of this type an object of my present invention is to simplify the mechanism of that disclosed in my patent above mentioned to make this more compact and to shift the arms with a less number of moving parts.

In this connection a further object of my invention is to employ a pair of beams each rotated by a separate gear on the pivot shaft carrying the arms; one of these beams being used to shift each of the arms in succession from an upper to a lower from an initial to a terminal position until these have all been shifted, and the other beam being used to return the complete stack of housed arms from the terminal to the initial position. In this operation a still further object of my invention is to oscillate both of the beams in the movement of shifting the individual arms from the initial to the terminal position and in the return movement of the beams, but to have the return movement beam operate idly on its return stroke until the complete stack of arms have been shifted from the initial to the terminal position. In this connection a detail feature and object of my invention is the employment of a cam structure on the last individual arm to be shifted, this cam operating a detent which, when actuated by the cam, shifts into position to engage the return movement beam so that this beam on its return action carries the whole stack to the initial position. In connection with the

movement of the beams a further object and detail feature of my invention is operating these through a gear system whereby the forwardly shifting beam operates through a lesser arc than the return movement beam, and both of such beams being controlled by a single cam through a different system of gear drive.

In connection with the gear drive to the beams for shifting the arms a further object and feature of my invention is the driving of a cam by an electric motor, and this cam being utilized to operate a rack in a longitudinal motion. This rack has two gears thereon each driving a pinion, one pinion being mounted on the vertical pivot shaft carrying the shiftable arms, and such pinion having the beam for forwardly shifting the arms attached thereto. The rack also drives through the second pinion and gear train which actuates the return movement beam, thereby simplifying the driving mechanism.

A further detail object and feature of my invention is in utilizing a secondary cam rotated from a main drive shaft which rotates with the main cam, and such secondary cam is utilized to raise and lower the beam forwardly shifting the arms to lift this over the stack of arms on its return movement.

My invention is illustrated in connection with the accompanying drawings in which:

Fig. 1 is a plan taken in the direction of the arrow 1 of Fig. 2 showing the stack of arms in the initial position.

Fig. 2 is a front elevation taken in the direction of the arrow 2 of Fig. 1.

Fig. 3 is a view similar to Fig. 1 with one of the arms moved to the terminal position.

Fig. 4 is an elevation of Fig. 3 in the direction of the arrow 4.

Fig. 5 is a plan similar to Fig. 3 with the beams in the position for shifting a second arm in a forward direction.

Fig. 6 is a side elevation taken in the direction of the arrow 6 of Fig. 5.

Fig. 7 is a horizontal section on the line 7—7 of Fig. 8 in the direction of the arrows.

Fig. 8 is a vertical section on the line 8—8 of Fig. 7 in the direction of the arrows.

Fig. 9 is a detail, vertical section on the

line 9—9 of Fig. 4 in the direction of the arrows.

Fig. 10 is a detail, vertical section on the line 10—10 of Fig. 5 in the direction of the arrows.

Fig. 11 is a detail, vertical section on the line 11—11 of Fig. 5 in the direction of the arrows.

Fig. 12 is a plan view similar to Fig. 3 with two of the arms moved to the terminal position.

In my invention I utilize a suitable supporting table 11 having legs 12 or the like, and extending upwardly from this table there is a vertical pivot shaft 13 which is illustrated as having a bottom thrust bearing 14 secured to the top of the table adjacent one edge, and at the top has a journal yoke 15 which is secured to a transverse bar 16 supported on lateral posts 17, these posts being connected to the marginal portions of the table adjacent the front. An arcuate track 18 is secured to the posts 17 and has a vertical web 19 with a horizontal outstanding flange 20. Such track is formed, preferably, of a T-shaped iron bent into a semi-circle.

The stack of arms designated at 21 is built up of a plurality of individual arms, each having the inner end horizontal as indicated at 22 and the outer end vertical as indicated at 23, with an intermediate quarter bend 24. These arms have perforations 25 through the center and are loosely mounted on the pivot shaft 13. Each of the arms bears on the upper edge 26 of the web 19 of the track 18, and each arm is utilized to suspend an advertising card 27.

For purposes of convenience the side of the machine at which the arms are stacked prior to individual movement is designated the initial side 28 and the opposite side to which the arms are moved and again formed into a pack or stack is designated the terminal side 29.

When the arms are stacked, for instance, at the initial position, the rearwardmost arm is also the lowest on the vertical shaft and the forwardmost arm is the uppermost. The rear arm has an angle bracket 30 secured thereto, this bracket having a horizontal flange 31 which extends underneath the complete pack of arms and is provided with a socket having a ball 32 therein, this ball bearing on the horizontal flange 20 of the track 18. The forwardmost arm has a plate 33 secured thereto and on this plate there is a pivot detent designated 34. This detent is in the form of a bell crank and is pivoted at 35, having a weighted end 36 and a downwardly projecting end 37. A cam plate 38 is secured to the rearwardmost arm when at the initial position, this cam plate having a vertical flange 39 secured to the back of such arm and a horizontal flange 40, this hori-

zontal flange having a cam edge 41. The cam edge engages the downwardly projecting end 37 of the detent 34 and holds this in a vertical position as illustrated in Figs. 2, 7, and 8, but when the first arm is moved by the mechanism hereinunder detailed from the initial to the terminal position the detent is allowed to tilt to the position indicated in Fig. 4.

The forward motion to the arms is given by the forwardly shifting beam which is designated at 42. This arm has a perforation 43 on its inner end and is secured to an elongated pinion 44, the pinion and beam being freely rotatable on the vertical pivot shaft 13. This beam has a downwardly turned finger 45, such finger having a rabbet 46 at the lower edge, the rabbet being adapted to engage the upper rear corner of the uppermost arm, which arm will be the forwardmost of the stack.

The drive mechanism for operating the pinion 44 comprises an electric motor 47 operating a worm 48 on a worm shaft 49. This worm operates a worm gear 50 secured to a vertical shaft 51 which is illustrated as having a socket bottom bearing 52 (note Fig. 6). A cam 53 is mounted on the upper portion of this shaft and this cam has a channel-shaped cam track 54. One portion 55 of this track is circular and of a large diameter, the opposite end 56 of the track is of a smaller diameter, and there are straight sections 57.

A rack bar 58 has a roller 59 secured thereto, this roller operating in the cam track. The rack has a sliding bearing in a bracket 60 and has a series of teeth 61 engaging the pinion 44. On rotation, therefore, of the cam, the rack is reciprocated and actuates the pinion 44 in opposite directions, thus moving the forwardly shifting beam 42 in an oscillating motion.

It is necessary to raise and lower this beam in this oscillating motion and this is done by providing a flange 62 on the upper part of the pinion 44, which flange is engaged by a roller 63 on a pivotally mounted lever 64, this lever having a pivot on a bracket 65 depending from the transverse bar 16. The opposite end of this beam has a roller 66 which engages a cam 67 carried by a horizontal cam shaft 68, this shaft being journaled in a front bracket 69 secured to the bar 16 and to a rear bracket 70 secured to the table of the machine. The cam shaft has a beveled gear 71 which meshes with a beveled gear 72 on a horizontal drive shaft 73, which latter has a bearing bracket 74 extending upwardly from the table, and a second bearing 75 in a large bracket 76 extending upwardly from the table. There is a beveled drive 77 from the vertical shaft 51 to the shaft 73 and, hence, to the cam shaft 68, actuating the cam 67. This cam in its motion is so designed that it lowers the beam 42 when this is in the initial

position of Figs. 1 and 2 for carrying the arms in a forward direction, in which case, as above mentioned, the rabbet 46 engages the horizontal portion of the forwardmost arm, 5 and as the beam is oscillated it carries this arm to the terminal position, the arm sliding on the upper edge of the track. On the return movement of the arm 42 the cam operates to raise the pinion 44 and, hence, the finger 45, 10 so that this will clear the pack of arms at the initial position on the return stroke. By this construction this forwardly feeding beam 42 shifts each arm of the stack in succession from the initial to the terminal position.

15 The mechanism for returning the stack or pack of arms comprises a return motion means 78. This is illustrated as being secured to the pivot shaft 13 by a key 79; and there being a driving gear 80 also keyed to this 20 shaft. However, if desired, the gear may be loose on the shaft with the beam 78 connected thereto. This beam has an upwardly extending finger 81 at its outer end. This finger clears the underside of the stack of arms but 25 the lower part 37 of the detent 34 is in the path of movement of this arm when such detent has this portion vertical as illustrated in Figs. 2 and 8. When the detent is tilted, as illustrated in Fig. 4, the finger 81 does not 30 engage such detent.

The motion is conveyed to the return shifting beam 78 by means of rack teeth 82 on the rack bar 58, these teeth driving a pinion 83 on a vertical shaft 84. Such shaft is 35 journaled in a bracket 85 extending upwardly from the table and also by a lower socket journal 86 on the table. The shaft 84 has a gear 87 at the bottom which meshes with the gear 80 and this causes the oscillation of such 40 gear and of the return motion beam 78. A feature of the motion of this beam is that it is through a greater arc than the motion of the forwardly shifting beam, and it moves past the stack of beams at the terminal position, 45 as illustrated in Figs. 3 and 7.

As above mentioned, when the complete stack of arms are at the initial position the projecting end 37 of the detent 34 is held vertically by the cam 38 but when the first 50 arm is oscillated from the initial to the terminal position this detent may swing into the tilted position of Fig. 4 and thus the finger 81 of the beam 78 may swing past and underneath the various arms as they build up 55 the pack at the terminal position. However, when the rearwardmost or last arm is moved, this arm having the cam 38, this cam shifts the detent, bringing the projecting end 37 vertically so that when the return motion 60 beam 78 starts on its motion from the terminal to the initial position the finger engages the projection 37 and moves the whole stack or pack of arms from the terminal to the initial position.

65 The machine provides sufficient time for

the advertising on the last two cards to be read in that the return motion beam and the forward feeding motion beam make a complete oscillation cycle after the last arm has been shifted to the terminal position, and 70 for this purpose the nose or leading edge 45A of the finger 45 extends a considerable distance forwardly of the end of the rabbet 46 on the lower edge of this finger, and when each arm in succession is moved to the terminal position it is only carried as far as it will be moved by the engaging edge of the rabbet. This leaves each arm at the terminal position in the location indicated in full lines in Figs. 3, 5, and 7, and as the forward 75 movement beam carries succeeding arms the nose 45A shifts these from the dotted line position of Fig. 7 or the full line position of Figs. 3 and 5 to the full line position of Fig. 7, or to the final position indicated by the first 80 arm moved in Fig. 12.

Thus, after all of the arms have been carried over from the initial to the terminal position, the last arm to be moved is left spaced from the group of arms as indicated by the dotted line in Fig. 7 so that the cam does not act on the bell crank detent and, thus, the return motion beam can swing another oscillation, and it is only when the forward motion beam moves from the initial to the terminal position without carrying an arm that the nose on the finger thrusts the last arm to be moved into close contact with the pack and thus shifts the detent 37 into position to engage the finger 81 on the return motion beam. 85

In order that the pack of arms may be easily returned, each arm as it reaches the terminal position is thrust up a slight slope 26A onto a raised edge 26B of the upper edge of the arcuate track (note Fig. 11). Therefore, when the single track or carriage 30 is shifted by the movement of the last arm to be moved from the initial to the terminal position, this carriage is readily thrust underneath the stack of arms, the elevation 26B being slightly above that of the edge 26 of the track. When the carriage 30 is returned to the initial position there is a slight depression 32A in the flange 20 of the track which receives the supporting balls 32, and this allows the arms to be readily shifted in succession without exerting such a pull on the carriage that the carriage on the last arm would be shifted. One of the features in 105 having the return motion beam move faster than the forward motion beam is so that when the arms are fed in a forward direction this return motion beam will clear the bell crank detent on the leading arm and will have no 110 effect in holding this arm back. 115

Various changes may be made in the details of construction without departing from the spirit or scope of the invention as defined by the appended claims. 120 125 130

I claim:

1. A display machine comprising in combination a stack of arms each adapted to support advertising matter and arranged to oscillate on a pivot, a pair only of shifting beams, means to oscillate said beams in part of a circle, means to engage one of said beams with each arm in succession to move such arm from an initial to a terminal position, and 5 after all of the said arms have been moved to said terminal position, means operative to engage the other beam to return the stack of arms from the terminal to the initial position.
- 15 2. A display machine as claimed in claim 1, the said beams moving in an oscillation on the same pivot and at the same time, and means to move the return motion beam in a greater arc of a circle.
- 20 3. A display machine comprising in combination a vertical pivot having a plurality of arms pivoted thereon, said arms being adapted to support advertising matter and arranged in the form of a stack, a single forward and a single return motion beam mounted on the same pivot, means to oscillate said beams, means to interengage the forward motion beam with each arm in succession to move such arm from an initial to 25 a terminal position in the arc of a circle, means to substantially simultaneously oscillate the return motion beam, means connected to the stack to permit free oscillation of the return motion beam during such oscillations of the forward motion beam from the stack of arms until the complete stack have been shifted from the initial to the terminal position, the said means connected to the stack causing an interengagement of the return motion 30 beam with the stack of arms on its reverse motion to return the stack of arms from the terminal to the initial position.
- 35 4. A display machine comprising in combination a vertical pivot having a stack of arms pivoted thereon to swing in a horizontal plane and each adapted to carry advertising matter, a single forward and a single return motion beam oscillatable on the same pivot, means to interengage the forward moving beam with each arm in succession starting with the forwardmost arm to shift such arm from an initial to a terminal position, means to elevate such arm over the stack on its return motion, means to oscillate the return motion beam at substantially the same time as the forward motion beam, and means connected to the stack operative to interengage the stack of arms and the return motion beam only after such stack have been all moved 40 from the initial to the terminal position, said return motion beam in its return shifting the said stack from the terminal to the initial position.
- 45 5. A display machine comprising in combination a vertical pivot shaft having a stack of arms extending radially therefrom and pivoted thereon, each arm being adapted to support advertising matter, a single forward and a single return motion beam oscillatable on the same pivot, means to convey a vertical motion to the forward motion beam, means to successively engage the forward motion beam with each of the arms in succession to move same from an initial to a terminal position, means to substantially simultaneously oscillate the return motion beam, and means mounted on one of the arms to interconnect the return motion beam and the stack of arms to return such stack from the terminal to the initial position only after the complete stack have been positioned at the said terminal position.
- 55 6. A display machine comprising in combination a stack of arms each rotatable on the same vertical pivot and each adapted to carry advertising matter, a forward motion and a return motion beam oscillatable on the same pivot, means to raise and lower the forward motion beam, the said beam being lowered on its forward motion to engage each arm in succession and being lifted on its return motion, the said beam shifting each arm from an initial to a terminal position, means to oscillate the return motion arm at substantially the same time as the forward motion arm but through a greater arc, a detent mounted on one of the arms and adapted to allow free movement of the return motion beam, and means connected with another arm to shift said detent into position to engage the return motion beam after the complete stack have been shifted to the terminal position and on the reverse motion of the return motion beam.
- 60 7. A display machine comprising in combination a vertical pivot having a plurality of radially extending arms adapted to form a stack at an initial and a terminal position, each arm being adapted to support advertising matter, a single forward and a single return motion oscillating beam mounted on the same pivot, means to oscillate said beams in a forward motion from the initial to the terminal position and in a reverse motion from the terminal to the initial position, means to interengage the forward motion beam and the arms only on its forward motion, means mounted on the stack to disengage the return motion beam and the said stack of arms on its forward and return motion until the complete stack have been shifted to the terminal position, the said means then interengaging the return motion beam and the stack to return said stack to the initial position on the return motion of the return motion beam.
- 65 8. A display machine comprising in combination a vertical pivot, a plurality of arms pivoting thereon and extending therefrom, said arms being adapted to form a stack and each to support advertising matter, an oscil-

- lating forward motion beam on the same pivot, means to oscillate said beam, means interengaging the said beam and the forward-most arm to shift each arm in succession from an initial to a terminal position, an oscillating return motion beam operating on the same pivot, a detent mounted on the forward-most arm and a cam on the rearwardmost arm, said cam and detent being operative to position the detent to interengage the return motion beam for the complete stack of arms located at the terminal position, the return motion of the return motion beam conveying the stack of arms from a terminal to an initial position. 10
9. A display machine comprising in combination a vertical pivot shaft, a plurality of arms pivoting thereon and extending therefrom and adapted to form a stack of arms and each adapted to carry advertising matter, a single forward motion beam and a single return motion beam each having a gear rotatable on the same pivot shaft, a master cam with a connection to oscillate each gear and thereby oscillate each beam, a secondary cam having means to raise and lower the forward motion beam for moving the arms in succession from an initial to a terminal position and to free such beam of such arms on its return motion, and means mounted on the said arms and adapted to interconnect with the return motion beam only after the stack of arms is located at the terminal position, the return motion beam being adapted to return the stack to the initial position on its return motion. 15
10. A display machine comprising in combination a vertical pivot, a stack of arms pivoted thereon to swing in a horizontal plane, a single forward motion beam having means to engage each arm in succession and move same from an initial to a terminal position, the said arms being oscillated from a position engaging a rear portion of each arm at the initial to a position in front of the terminal position, a single return motion beam, means to oscillate said beam from a position in front of the initial position to a position rearwardly of the terminal position of the said arms, and means operative after the complete stack of arms have been shifted from the initial to the terminal position to interconnect said stack and the return motion beam to shift the stack as a unit from the terminal to the initial position. 20
11. A display machine comprising in combination a vertical pivot, a stack of arms pivotally mounted thereon, a forward motion beam and a return motion beam each pivotally mounted on the said pivot, the first being above the stack and the latter below the stack of arms, means to oscillate the forward motion beam and to raise and lower said beam to engage each arm in succession and shift same from an initial to a terminal 25
- position, means to substantially simultaneously oscillate the return motion beam, said beam passing underneath the arms at the terminal position, and a depending means attached to one of the arms and actuated by the last arm to be moved to locate said depending means to interengage with the return motion beam on its return motion to shift the stack as a whole from the terminal to the initial position. 30
12. A display machine as claimed in claim 11, the depending means comprising a weighted bell crank pivotally mounted on the first arm to be moved from the initial to the terminal position, the last arm to be moved having a cam to engage the bell crank and shift the same into engaging position with the return motion beam. 35
13. A display machine comprising in combination a vertical pivot having a stack of arms each arm having a horizontal section with a perforation therethrough for the pivot and each arm having a vertical section with a quarter bend between said sections, a forward motion beam oscillating on the same pivot and being shiftable vertically and having means to engage the uppermost horizontal portion of an arm and to shift the arm engaged from an initial to a terminal position, and means operative after the stack of arms have been shifted to the terminal position to return such stack to the initial position, the means to return the stack comprising a return motion beam oscillating on the same pivot, a pivotally mounted detent on the vertical face of the first arm to be moved, said detent being shiftable to allow passage of the return motion beam, and a cam secured to the last arm to be moved and shifting the detent into a position to be engaged by the return motion beam for the return of the stack. 40
14. A display machine comprising in combination a vertical pivot shaft having a stack of arms pivoted thereon to swing in the arc of a circle, a master cam, a rack bar operative thereby, an upper pinion on the pivot shaft, a forward motion beam connected to said pinion, a gear on the pivot shaft below the stack, a single return motion beam connected to said latter gear, the said rack operating the pinion directly and having a gear train to operate the said gear, the forward motion beam having means to shift each arm in succession from an initial to a terminal position, and the return motion beam engaging with means on the stack to return the arms to the initial position. 45
15. A display machine comprising in combination a plurality of arms partly rotatable on a common pivot, said arms being adapted for packing in a stack, means to move each arm in succession from an initial to a terminal side of the machine by a forward stroke, said means leaving each arm slightly 50

spaced from its terminal position, and on a succeeding forward stroke thrusting an arm formerly moved to its terminal position.

16. A display machine comprising in combination a vertical pivot having a plurality of arms pivoted thereon, each arm having a horizontal section and a vertical section with a quarter turn, the arms being adapted to be formed into a stack, an oscillating forward motion beam having means to engage the horizontal portions of each arm in succession and shift these from an initial to a terminal side of the machine, said beam leaving each arm slightly spaced from its terminal position, and means on the said beam to engage an arm formerly moved on a succeeding stroke in a forward direction and to thrust such arm to its complete terminal position.

17. A display machine comprising in combination a plurality of pivotally movable arms each mounted on the same pivot and being adapted to be formed into a stack and each arm adapted to support advertising matter, means to move each arm in succession in a forward stroke from an initial to a terminal position until all of the arms have been shifted to such terminal position, a return motion means operating idly during the forward motion of each arm, and means operative after the last arm has been moved to the terminal position to move the return motion means a complete cycle from the terminal to initial positions and back, and means on the stack to then interengage the return motion means and the stack of arms to shift said arms to the initial position.

18. A display machine comprising in combination a common pivot having a plurality of arms mounted thereon for carrying advertising matter, a single forward motion and a single return motion beam pivoted on the same pivot, means to interengage the forward motion beam and each of the arms in succession to move the said arms from a stack in the initial position to form a stack at the terminal position, means to oscillate the return motion beam at the same time as the forward motion beam but at greater speed, means operative after the last arm has been shifted to give a double stroke to the return motion beam and means on the stack to then interengage said beam with the stack of arms and return said arms to the initial position.

19. A display machine comprising in combination, a pivotally mounted stack of arms, means to move such arms one by one from an initial to a terminal position, a pivotally mounted return motion beam with means to oscillate said beam in an arc from in front of the initial position of the stack to behind the terminal position of the stack, and means after the complete stack have been moved from the initial to the terminal position to return the stack by the return motion beam.

20. A display machine comprising in combination, a central common pivot, a plurality of arms pivoted thereon and adapted to form a stack, means to move each arm in succession from an initial to a terminal position, a return motion beam pivoted on the same pivot with means to oscillate said beam from in front of the initial position to behind the terminal position of the stack, and means operative with the said beam after the stack has been moved to the terminal position to return such stack to the initial position.

21. A display machine comprising in combination, a plurality of pivotally mounted arms adapted to form a stack, means to move said arms one by one from an initial to a terminal position, a return motion beam having a pivotal mounting, means to oscillate said beam from in front of the initial position to behind the terminal position of the stack, and means mounted on the stack and engageable by the said beam to return the stack as a unit from the terminal to the initial side of the machine.

22. A display machine as claimed in claim 21, the means mounted on the stack comprising a weighted bell crank pivoted on one of the arms of the stack, a cam on another of said arms to operate said bell crank to move one of the arms of the same to be engaged by the return motion beam.

23. A display machine comprising in combination, a plurality of pivotally mounted arms each having a flat horizontal section and a vertical section adapted to support display cards, the said arms being adapted to form a stack with the horizontal section superimposed, a forward shift beam pivotally mounted, with means to oscillate said beam in an arc and to raise and lower the beam to engage the horizontal section of each arm in succession and to move the arms from an initial to a terminal position, a return motion beam pivotally mounted, with means to oscillate said beam from in front of the initial to back of the terminal position of the stack, and means mounted on the stack engageable by the return motion beam after the stack is complete at the terminal side to return such stack as a unit to the initial position of the machine.

24. A display machine comprising in combination, a central common pivot having a plurality of arms pivotally mounted thereon adapted to form a stack, each arm having a horizontal section, a forward shifting beam mounted on the same pivot, with means to oscillate said beam and to raise and lower said beam to move such arms from an initial to a terminal position in succession by engaging the horizontally flat portions of each beam, said beam returning from the terminal to the initial position, a return motion beam pivotally mounted on the same pivot, with means to oscillate said beam from in front

of the initial to back of the terminal position of the stack, means on the first arm moved from the initial to the terminal position adapted to interconnect with the return motion beam, said means being normally out of the path of such beam, and a cam on the last arm moved from the initial to the terminal position to shift the said means to engage the return motion beam whereby such return motion beam may return the stack as a whole from the terminal to the initial position.

In testimony whereof I have signed my name to this specification.

15 THOMAS S. S. WAGNER.
